CLAIM

The customizable marketing apparatus with a trapezoid cutout, as shown and described.

DESCRIPTION

FIG. 1 is a front, facing view of an unfolded customizable marketing apparatus with a trapezoid cutout including our design;

FIG. 2 is a front, facing view of the unfolded customizable marketing apparatus with a trapezoid cutout with three tabs extending from the left most flap folded in according to our new design;

FIG. 3 is a bottom profile view thereof;

FIG. 4 is a front, facing view thereof with the rightmost flap folded in;

FIG. 5 is a bottom profile view thereof;

FIG. 6 is a front, facing view thereof with the rightmost flaps folded in and the leftmost flap folded in;

FIG. 7 is a bottom profile view thereof;

FIG. 8 is a rear, facing view thereof with the two rightmost flaps folded in and the leftmost flap folded in;

FIG. 9 is a bottom profile view thereof;

FIG. 10 is a front, perspective view thereof with an open front flap; and,

FIG. 11 is a front, perspective view with a closed front flap.

The broken line showing of elements on the customizable marketing apparatus with a trapezoid cutout illustrate fold lines.
